UNITED STATES PATENT OFFICE.

EZRA DIXON, OF BRISTOL, RHODE ISLAND.

WEIGHT-LEVER FOR SPINNING-MACHINES.

1,078,996.

Specification of Letters Patent.

Patented Nov. 18, 1913.

Application filed November 25, 1911. Serial No. 662,286.

To all whom it may concern:

Be it known that I, EZRA DIXON, a citizen of the United States, residing at Bristol, in the county of Bristol and State of Rhode Island, have invented a new and useful Improvement in Weight-Levers for Spinning-Machines, of which the following is a specification.

This invention pertains to certain new and useful improvements in weight levers for spinning machines, and relates more particularly to the means for permitting adjustment between the arms or parts of the lever.

The primary object of the invention is to provide improved, novel and efficient means for connecting the arms of the lever so that same will be positively held in any position to which they may be moved or adjusted, and which will at the same time permit adjustment to be accomplished with ease and facility.

In the drawings,—Figure 1 is a side elevation, partly in section of a part of a spinning machine equipped with the present invention. Figs. 2 and 3 are detail perspective views of the two parts or arms of the lever. Fig. 4 is a section on the line 4—4 of Fig. 1 and Fig. 5 is a perspective view of a modified form of one of the arms or parts.

The frame of the machine is indicated at 1 in the drawings and supports the standard 2 on which the lower rolls 3 and the upper rolls 4 are mounted. The arms 5 and 6 bear on the upper rolls and the arm 5 has a strap 7 connected thereto, the lower end of which is connected to the weight lever generally designated 8 in the drawings.

The weight lever is composed of two arms or parts 9 and 10, the part 9 having a hook-shaped end 11 which engages through an eye 12 secured to the frame 1. The arm 9 is formed with a series of slots 13 which extend longitudinally thereof, and which have central enlarged portions 14, that extend on opposite sides of the slots as clearly depicted in Fig. 2 of the drawings. In other words the openings 14 may be said to comprise a circular hole that is crossed by a slot 13. A hook 15 is carried by the rear end of the arm 9 and engages in one of a series of slots 16 that extend up through the bottom edge of the arm 10, the slots 16 having their outer ends or mouths widened so as to easily receive the hook 15. The

upper or top edge of the arm 10 is formed at its rear end with a slot 17 to receive the arm 18 from the lower end of which the weight 19 is suspended. The front end of the arm 10 is formed with a T-shaped head or stud 20 the thickness of which is such as to permit the head to be turned so that the arm 10 extends at right angles to the arm 9 whereupon the head 20 is introduced into the slot 13, and then turned to assume the position shown in Fig. 1 of the drawings, in which it will be noted that the outer end of the arm 10 seats in the hook 15, as shown more clearly in Fig. 4 of the drawings. The length of the head is such that same may easily enter the slots 13, and the shank of head 20 is caused to occupy the aperture 14.

The modification disclosed by Fig. 5 of the drawings proposes the use of but one slot 21, that is made sufficiently long so as to connect the several openings 14. In this form of the invention the head 20 is introduced into the slot 21 and is then moved therewith until the desired opening 14 has been reached, after which the arm is turned to unite the parts as shown in Fig. 1 of the drawings.

Having thus described my invention, I claim as new and desire to secure by Letters Patent:—

1. In a weight lever for spinning machines, a pair of arms, one of said arms having a series of downwardly facing notches therein, a T-shaped head on one end of said arm, and the opposite end of said arm having a notch therein to suspend a weight therefrom, the other arm having an upwardly extending hook formed on one end to engage in one of said notches of the first mentioned arm and also having an aperture therein and a slot that is disposed longitudinally of the arm and extends on opposite sides of the aperture through the latter.

2. In a weight lever for spinning machines, a pair of arms, one of said arms having notches therein, a T-shaped head on one end of said arm, the other arm having an upwardly extending hook to engage in one of the notches of the first mentioned arm and the outer side of the latter and also having an aperture crossed by an elongated slot that extends on opposite sides of said aperture the shank of the head being received in the aperture.

3. In a device of the type set forth, a pair of arms one of the arms having a series

of notches and a T-shaped head on its inner end, the other arm having an upwardly extending hook which engages the bottom edge and the outer face of the first mentioned arm, and also having an aperture crossed by a slot to receive said T-shaped head and to permit the latter to be turned to bring the shank of the head in said aperture the shank of the head being received in the aperture.

4. In a weight lever for spinning machines, a pair of arms, one of the arms having an aperture crossed by a slot and the other arm having a T-shaped head, the slot

being of a length to permit the head to be passed therethrough and then turned to cause the shank of the head to occupy the aperture, the head engaging the outer side of the first named arm, and means carried by the first named arm to engage the outer face of the second named arm.

In testimony whereof I have signed my name to this specification in the presence of two subscribing witnesses.

EZRA DIXON.
